UNITED STATES PATENT OFFICE.

ALBERT GEE, OF OAK LANE, PENNSYLVANIA.

STOP DEVICE FOR FULL-FASHIONED STOCKING-KNITTING MACHINES.

Application filed October 29, 1920. Serial No. 420,534.

To all whom it may concern:

Be it known that I, ALBERT GEE, a citizen of the United States, residing in Oak Lane, Philadelphia County, Pennsylvania, have invented certain Improvements in Stop Devices for Full-Fashioned Stocking-Knitting Machines, of which the following is a specification.

My invention relates to improvements in stop devices for knitting machines, the object of my invention being to provide means for stopping the machine which is automatically operable when a predetermined length of the knitted material has left the needles, whereby articles of uniform length may be obtained regardless of the factors of variability which are always present in knitting operations of machines of the type involved.

In the attached drawings:

20 Figure 1, is a front elevation of a portion of a full fashioned stocking knitting machine equipped with a stop device made in accordance with my invention;

25 Fig. 2, is a plan view of that portion of the knitting machine shown in Fig. 1;

Fig. 3, is a vertical section taken on the line 3—3 Fig. 1, and

30 Fig. 4, is a view in perspective of the chain carrying sprocket showing the details of the clutch device associated therewith.

With reference to the drawings, 1 indicates the frame of the machine, and 2 the main driving shaft mounted in suitable bearings therein. Slidably mounted in the said frame 1 is a starting rod or lever 3, said rod being operably connected in the present instance with a belt shifter (not shown) adapted to shift the belt from a tight to a loose pulley in stopping the machine and from the said loose pulley to the tight pulley in starting. Also mounted in suitable bearings in the said frame 1 is a shaft 4 which carries a fabric reel 5 of the well known form, and also fixed to the said shaft 4 is a pulley 5^a upon which may be wound a cord 6 which, in the present instance, passes over a fixed pulley 7 and has attached to the extremity thereof suitable weights 8, said weights by gravity and through the cord 6 exerting a force upon the pulley 5^a tending to rotate the shaft 4 and the fabric roller 5 in a given direction. The free end of the knitted fabric is attached in the usual manner to the roller 5, said fabric as it leaves the needles being rolled up upon the roller and being kept taut with a constant

tension by the aforescribed action of the weights 8.

Fixed to the shaft 4 is a sprocket wheel 9 upon which rides an endless chain 10, said chain depending loosely from the said sprocket, while pivotally attached to the frame 1 at 11 is a member 13 having a downwardly extending lug or tooth 14 which normally rests upon the upper surface of the chain 10 where it passes over the sprocket 9, in the manner shown in Fig. 3. In one or more of the links 10^a of the chain 10 is a niche or recess 10^b, said niche or recess being of such size as to accommodate the said tooth 14 on the frame 13. It will be clear from the foregoing that so long as the tooth 14 rests upon the surface of the chain the member 13 is retained in an elevated position, but when as the sprocket revolves a recessed link 10^a is brought to the top, the said tooth 14 will enter the recess 10^b with a resultant depression of the member 13.

Secured to the rod 3 is a block 15, while loosely mounted and adapted to slide upon the said rod is a loose block 16, said block 16 having an arm 16^a adapted to fit within a corresponding groove 15^a in the said block 15 whereby rotation around the rod is prevented. A coiled spring 17 carried upon the rod 3, is confined between a portion 1^a of the frame 1 and the end of the block 16 and exerts a force tending to keep the said block in contact with the said block 15. An arm 18 pivotally secured to the block 16 extends laterally and forwardly thereof, and carries upon its end a roller 19 overlying an arm 13^a pivotally attached at 12 to the frame 1 and having the free end thereof suitably supported by the member 13, said arm 13^a having fixed thereto a suitable lug 20, against the edge of which the roller 19 is adapted to lie, and which, when the said member 13 is in an elevated position, as it is when the tooth 14 rests upon the upper surface of the chain 10, acts as a stop preventing movement of the block 16 upon the rod 3 under the action of the spring 17. In the present instance, the member 13 has a laterally and downwardly extending outer end portion in which is an aperture 13^b, and a suitable extension 13^c upon the end of the arm 13^a fits loosely within said aperture, thereby establishing the necessary connection between the member 13 and the arm 13^a. Extending from the side of the block 16 is a pin 29, while threaded in and extending through the

arm 18 is a screw 30, the lower end of which is adapted to engage the said pin 29 to limit the downward motion of the arm 18. The object of the limiting device is to permit 5 the lug 20 to fall sufficiently far below the roller 19, when the member 13 is depressed to insure the release of the roller, the device, at the same time, not interfering with the upward movement of the arm to permit 10 the roller to ride over the top of the lug 20 when the rod 3 is shifted to the starting position. The extent of the said downward movement of the arm may be regulated by adjustment of the screw 30. It will be clear 15 that when the said member 13 is in the elevated position, the rod 3 may be shifted to the left without disturbing the block 16, which is retained in the normal position in the manner described above.

20 The operation of the device in so far as described is as follows:

The usual provision being made for attaching the knitted fabric to the roller 5, the machine is started by shifting the rod 3 25 to the right, the various elements assuming the positions in which they are shown in Fig. 2. The chain 10 has previously been set, in a manner hereinafter described, in such manner that the shaft 4 must rotate through 30 a predetermined angle before a link 10^a containing the said recess 10^b is advanced to the top of the sprocket in position permitting the tooth 14 of the member 13 to enter the said recess, the tooth 14 in the meantime resting upon the upper surface of the chain whereby the member 13 is supported in the elevated position. In this position of the member 13, the roller 19 abuts the lug 20 upon the arm 13^a and thereby prevents movement of the 35 block 16 under the pressure of the spring 17. When, however, the said tooth 14, as in the manner heretofore explained, enters the said recess 10^b, the member 13 is depressed, thereby releasing the roller 19 from engagement 40 with the lug 20 and permitting the block 16 under pressure of the spring 17 to move to the left, said block by abutment with the block 15 which is fixed to the lever 3, forcing the lever to the left and thereby shutting 45 down the machine. If during the knitting operation and before the chain 10 has traveled sufficiently to carry the recess 10^b into position to be entered by the tooth 14, it is desired to bring the machine to a stop, this 50 may be done as previously explained, by manually shifting the rod 3 to the left which will in no way disturb the automatic stop mechanism.

Extending forwardly from the member 13 60 is a pin 21, said pin being adapted for engagement by cams 22 and 23 upon the shifting rod 3, the said cam 23 entering into engagement with said pin to elevate the member 13 when the rod is shifted to the left 65 or machine-stopping position, thereby ele-

vating the pin 14 from the depression 10^a which it occupies. The cam 22 is adapted to engage the pin 21 when the starting lever 3 is moved to the starting position to elevate the said member 13 and the pin 14 from the 70 said recess 10^b which it occupies, this being necessary in order to permit the machine to start. As soon as the machine is under way, the shifting rod 3 is released and by reason of the spring 17 assumes the normal going 75 position in which it is shown in Fig. 2, whereby the pin 21 is released from engagement with the cam 22 and the tooth 14 permitted once more to rest upon the surface of the chain. It will be seen that in starting 80 the machine the starting rod must be shifted to an extreme position and held there until the machine is under way, the rod then being released and automatically assuming an intermediate going position.

85 The sprocket 9 is loosely mounted upon the shaft 4, and connection between the said shaft and sprocket is effected by means of a collar 24 which is suitably secured, as by means of a set screw 25, to the said shaft 4, 90 and which has extending from the face thereof which abuts the hub 9^a of the sprocket 9, pins 26 which are adapted to enter corresponding recesses 27 in the said hub 9^a. A spring 28 is secured to the sprocket 9 and tends to retain the said sprocket in engagement with the said collar 24. It is clear that by shifting the said sprocket so as to remove the pins 26 from the recesses 27 in the hub, the sprocket may be rotated freely 100 upon the shaft 4 and the chain placed in any position that may be desired. If for any reason it is found desirable to rotate the shaft 4 independently of the sprocket, this may be accomplished by shifting the 105 sprocket on the shaft sufficiently to carry it into contact with a stop 31 fixed to the frame, said stop engaging the teeth of the sprocket and preventing its rotation.

110 The length of the knitted article will, of course, depend entirely upon the number of links intervening at the start between the tooth 14 and the link having a recess 10^b which lies nearest the tooth in the direction opposite to that in which the chain travels, and the length of the knitted article can accordingly be controlled.

115 Where the knitted article, as in the case of a full fashioned stocking, is formed in a number of distinct and consecutive operations, the portions of the stocking formed in said operations being of specified lengths, the chain may be divided into a number of sections corresponding respectively to the 120 lengths of the said sections of the stocking 125 and united by recessed links 10^a, so that at the end of each operation the machine automatically stops down.

130 The device not only makes it possible to obtain articles of exactly uniform lengths,

but also effects a substantial saving in materials in that the exact desired lengths are always assured and there is no overrunning. The device similarly avoids serious loss due 5 to the making of lengths so short as to be of no commercial value.

I claim:

In a knitting machine, the combination of a revolvable shaft, a fabric reel upon said 10 shaft adapted to take up the fabric from the needles and to retain it under tension, a sprocket upon said shaft, a chain carried by said sprocket, one or more of the links of said chain having a recess therein, a pivot- 15 ally mounted member having an element adapted to engage said chain whereby said member is retained in an elevated position, said pivoted member being depressed when

said element enters the said recess, means for halting the operation of said machine, an 20 operating member for said halting means, means operatively connected with said operating member for automatically shifting the said member to stop the machine, means carried by said pivoted member for retain- 25 ing said automatic shifting means in an in-operative position when the said pivoted member is elevated, said shifting means being released when the said pivoted member is depressed, and means carried by said op- 30 erating member for elevating the said pivoted member when the said operating member is shifted either to the machine-halting or starting positions.

ALBERT GEE.
